(57) **CLAIM**

The ornamental design for a MONITOR, as shown and described.

DESCRIPTION

FIG. 1 is a front perspective view of a Monitor, showing our new design;

FIG. 2 is a front view of the Monitor as shown in FIG. 1; FIG. 3 is a rear view of the Monitor as shown in FIG. 1; FIG. 4 is a left-side view of the Monitor as shown in FIG. 1; FIG. 5 is a right-side view of the Monitor as shown in FIG. 1;

FIG. 6 is a top view of the Monitor as shown in FIG. 1; FIG. 7 is a bottom view of the Monitor as shown in FIG. 1; FIG. 8 is a rear perspective view of the Monitor as shown in FIG. 1;

FIG. 9 is a front perspective view of the Monitor as shown in FIG. 1, as shown in an alternate position;

FIG. 10 is a front view of the Monitor as shown in FIG. 9; FIG. 11 is a rear view of the Monitor as shown in FIG. 9; FIG. 12 is a left-side view of the Monitor as shown in FIG. 9;

FIG. 13 is a right-side view of the Monitor as shown in FIG. 9;

FIG. 14 is a top view of the Monitor as shown in FIG. 9; FIG. 15 is a bottom view of the Monitor as shown in FIG. 9; FIG. 16 is a rear perspective view of the Monitor as shown in FIG. 9;

FIG. 17 is a front perspective view of the Monitor as shown in FIG. 9;

(Continued)

in FIG. 1, as shown in another alternate position; FIG. 18 is a front view of the Monitor as shown in FIG. 17; FIG. 19 is a rear view of the Monitor as shown in FIG. 17; FIG. 20 is a left-side view of the Monitor as shown in FIG. 17; FIG. 21 is a right-side view of the Monitor as shown in FIG. 17; FIG. 22 is a top view of the Monitor as shown in FIG. 17; FIG. 23 is a bottom view of the Monitor as shown in FIG. 17; and FIG. 24 is a rear perspective view of the Monitor as shown in FIG. 17. The even-dash broken lines illustrating portions of the Monitor form no part of the claimed design. The dot-dash broken lines defining the boundary of the claimed design form no part of the claimed design.

1 Claim, 24 Drawing Sheets
